UNITED STATES PATENT OFFICE.

HENRY H. SCHUETTE, OF NAPOLEON, OHIO.

ECCENTRIC.

1,144,731.

Specification of Letters Patent. Patented June 29, 1915.

Original application filed April 16, 1914, Serial No. 832,207. Divided and this application filed January 7, 1915. Serial No. 960.

To all whom it may concern:

Be it known that I, HENRY H. SCHUETTE, a citizen of the United States, and a resident of Napoleon, in the county of Henry 5 and State of Ohio, have invented a certain new and useful Eccentric; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to machine elements and particularly to an eccentric, and is a division of the application filed by me on April 16, 1914, Serial No. 832,207, for a grain separator.

20 The primary object of my invention is to give an eccentric a maximum throw without increasing the outside diameter thereof.

A further object of the invention is to provide simple and improved means for securing the eccentric to its shaft, whereby 25 to enhance the practicability and commercial value thereof.

The invention is fully described in the following specification, and while, in its 30 broader aspect, it is capable of embodiment in numerous forms, a preferred embodiment thereof is illustrated in the accompanying drawings, in which,—

Figures 1 and 2 are side and edge elevations 35 respectively of an eccentric embodying my invention. Fig. 3 is a cross-section thereof on the line x, x in Fig. 2. Fig. 4 is a section on the line y, y in Fig. 3. Fig. 5 is an edge view of the eccentric member, and Fig. 6 40 is a perspective view of the removable bearing block.

Referring to the drawings, 1 designates a shaft, 2 the eccentric member, which is keyed to the shaft, and 3 the strap member, 45 which rotatably encircles the eccentric member 2 and has the rod 4 projecting therefrom.

The eccentric member is of circular form and has its periphery circumferentially grooved, as at 5, to form a guide-way 50 for receiving the strap 3. The strap 3 is made in two parts which are secured together by bolts 6, or in any other suitable manner. The eccentric member 2 is pro-

vided at one side of its axis with a radially-disposed shaft receiving notch 7, which is of suitable depth to permit the shaft 1, when placed therein, to have its outer side substantially flush with the base of the groove 5, as shown in Figs. 1 and 3. A key seat 8 is 60 provided in the base of the notch 7 to receive a key 9, which also engages in a registering groove or key seat in the shaft 1.

The eccentric member 2 is secured to the shaft by means of a removable bearing 65 block 10 and U-shape binding clips 11. The block 10 is of suitable shape and size to fit into and fill the portion of the notch 7 without the shaft, and is of a length to extend at its ends beyond the respective sides 70 of the eccentric member, as shown in Figs. 2 and 4. The block 10 is provided in register with the edge flanges or side walls of the eccentric groove 5 with shoulders 12, and is cut away at its outer side between the 75 shoulders 12, 12 to a point in circular register with the base of the groove 5 to permit the eccentric strap 3 to freely turn over the block 10 and assist in holding such block to the shaft. The ends of the block 10 without the shoulders 12 are of segmental form 80 to adapt the looped portions of the clips 11 to engage thereover, as shown in Fig. 1. The legs of the clips project inward at the sides of the shaft and through registering 85 openings in respective flanges 14 which are formed on the sides of the eccentric diametrically thereof. Nuts 15 are threaded on the free ends of the clips 11 and coat with the flanges 14 to retain the clips in assembled relation.

It is evident with this form of eccentric and the manner of securing the same to the shaft that it is possible to place the outer edge of the shaft substantially flush or in 95 register with the inner peripheral line of the strap 3, thereby giving a maximum throw to the eccentric without increasing the outside dimensions of the strap. It is also evident that the eccentric can be easily and 100 quickly removed from or secured to a shaft for the purpose of substitution or repair.

I wish it understood that my invention is not limited to any specific construction, arrangement or form of the parts except 105 in so far as such limitations are specified in the claims.

Having thus described my invention, what

I claim as new, and desire to secure by Letters Patent, is,—

1. In combination, an eccentric member having a shaft receiving notch in an edge thereof, a shaft in said notch, a removable bearing block fitted into the outer end of said notch without the shaft and having its ends projected beyond the sides of said member, means engaging the extended ends 5 of said block and adjustably connecting it to said member, means for locking the shaft and member against relative turning, and an eccentric strap loosely encircling said eccentric member and block with its inner 10 periphery substantially flush with the outer side of the shaft.
2. In combination, an eccentric member having a shaft receiving notch in an edge thereof, a shaft keyed in the base of said notch, a bearing block closing the outer end 15 of said notch, an eccentric strap loosely encircling said eccentric member and block with its inner periphery substantially flush with the outer side of the shaft, and means 20 for securing the bearing block to the eccentric.
3. In combination, an eccentric member having a radial shaft receiving notch in an edge thereof, a shaft keyed in the base of 25 said notch, a bearing block seated in the outer end of said notch without the shaft

and having its ends projected beyond the sides of said member, clips embracing the extended ends of said block and adjustably attached to said member, and an eccentric 35 rotatably encircling said member and block.

4. In combination, an eccentric member having a radial shaft receiving notch in an edge thereof and having flanges projecting from opposite sides thereof adjacent to the 40 base of said notch, a shaft keyed in the base of said notch, a bearing block seated in the outer end of said notch against the outer side of the shaft and conforming at its outer side to the peripheral shape of the eccentric 45 member and having its ends projected beyond the sides of said member, U-shaped clips straddling the projected ends of said block and the shaft and having their free ends adjustably secured to said flanges, and 50 an eccentric strap rotatably embracing said member and bearing block with its inner periphery substantially flush with the outer edge of the shaft.

In testimony whereof, I have hereunto 55 signed my name to this specification in the presence of two subscribing witnesses.

HENRY H. SCHUETTE.
